CLAIM

The ornamental design for an in line compact appliance leakage current interrupter, as shown and described.

DESCRIPTION

FIG. 1 is a perspective view of an in line compact appliance leakage current interrupter showing our new design;

FIG. 2 is a top view of the in line compact appliance leakage current interrupter shown in FIG. 1;

FIG. 3 is a right side view of the in line compact appliance leakage current interrupter shown in FIG. 1;

FIG. 4 is a left side view of the in line compact appliance leakage current interrupter shown in FIG. 1;

FIG. 5 is a bottom view of the in line compact appliance leakage current interrupter shown in FIG. 1;

FIG. 6 is a right end view of the in line compact appliance leakage current interrupter shown in FIG. 1;

FIG. 7 is a left end view of the in line compact appliance leakage current interrupter shown in FIG. 1; and,

FIG. 8 is a perspective view of the in line compact leakage current interrupter of FIG. 1 in association with a three prong plug shown in broken lines.

The broken line showing of a cord and plug is for illustrative portions only and forms no part of the claimed design.
